COMBINED CHAIR AND WALKER

John Michelic, Chicago, Ill.

Application March 28, 1940, Serial No. 326,374

6 Claims. (Cl. 155—24)

This invention relates to certain new and useful improvements in a child's combined chair and walker.

My combined chair and walker is adapted for use by a normal child as a chair, or as a walker whereby the child may learn to walk. It is also especially adapted for use by a crippled, disabled or invalid child, and particularly by an infirm child of feeble body or lower limbs.

One of the objects of my invention is found in the provision of movably supported or portable combined chair and walker which is readily adapted for conversion into use as a child's chair or walker; which provides adequate support for the child in sitting, standing or walking postures; which cannot be tilted by the child; and one which is so constructed that it is practically impossible for the child to stand upon the seat thereof or to extricate itself therefrom.

Another object of my invention resides in the provision of a child's combined chair and walker having a laterally movable and adjustable seat whereby such device is readily convertible for use as a chair or walker, and the adjustment of which seat beyond the control of the child, and which device can be readily made of wood, metal or other suitable material and provided with a tray for toys or food receptacles, and manufactured at comparatively low cost in different sizes to meet the age requirements.

With the above and other objects in view, my invention consists in the novel combination, construction and arrangement of the parts and members shown in preferred embodiment in the appended drawing, described in the following specifications, and particularly pointed out in the appended claims.

In the drawing, in which like or corresponding parts are indicated by like reference numerals:

Fig. 1 is a front elevation of a combined walker and chair embodying my invention;

Fig. 2 is a side elevation of same;

Fig. 3 is a plan view of same;

Fig. 4 is a partial vertical section showing the seat in Fig. 2 moved rearwardly when the device is used as a walker;

Fig. 5 is a partial vertical section similar to that shown in Fig. 4, but showing a modified seat and spring arrangement; and

Fig. 6 is a cross-section taken on line 6—6 of Fig. 5.

Referring to the embodiment of my invention as illustrated in Figs. 1 to 4 inclusive, the device includes a plurality of supporting legs, preferably four, and downwardly flaring to provide

a comparatively wide base. The front legs are indicated by numeral 10, and the rear legs by numeral 11.

A suitable tray 12 for food or toys is supported upon the upper portions of the legs 10 and 11. This tray 12 also constitutes a support for the arms of the child when the device is used as a walker in training children to walk.

The tray 12 is provided with a suitably shaped opening for the child's body. The opening has its marginal edge protected by a rubber cushion cover 13.

The rear legs 11 extend through and above the tray 12 to support a cushion type of head rest 14. Suitable casters 19, preferably of the ball-bearing type, are secured to the bottom of the legs 10 and 11 to facilitate movement of the device.

Suitably secured to and preferably suspended from the tray 12 is a depending enclosure 15 for the child's body. This enclosure consists of a rear wall 16, side walls 17 and a front wall 18, and these walls are disposed in close proximity to the child's body to thus support the child's trunk in vertical position.

Obviously, the enclosure 15 might be supported by any suitable strut connected to the rear legs 11 in addition to its supporting connection with the tray 12.

The front wall 18 is provided with a pair of spaced openings 20 for the child's legs, arranged to provide a depending spacer 21 which is adapted to be positioned between the child's legs when it is seated in the device to prevent the child from crossing its legs or rearranging its legs in an attempt to stand upon the seat 26.

The front portions of the sides 17, adjacent the openings 20, are provided with openings 22 which merge with the openings 20 to provide ample space for the legs of the child extended therethrough. As clearly shown in Figs. 1 and 2, each pair of openings 20 and 22 constitutes a corner opening.

The slidably adjustable seat 26, of substantially rectangular shape, is provided with a central forwardly disposed extension 28 which is disposed to be positioned between the child's legs, and which extension 28 cooperates with the depending spacer 21 to impede the child's self extrication from the device.

The front legs are stiffened by a horizontal strut 23, preferably of a round steel rod, which is secured to and between the front legs 10. A similar horizontal strut 24, of preferably a round steel rod, connects the rear legs 11. Other steel

rod struts 25 may be arranged to connect one of the front legs with one of the rear legs.

The front and rear struts, respectively indicated by numerals 23 and 24, also constitute supports for the seat 26.

The seat 26 extends between the side walls 17 for slidable support upon a pair of lugs 27 secured to the inner faces of the side walls 17 or formed integrally therewith.

As shown in Figs. 2, 3 and 4, a pair of coil springs 29 is provided which tend to pull the seat 26 rearwardly. Each spring 29 has one end attached to the under side of seat 26, as at 30, and the opposite end attached to the lug 27, as at 31.

As shown in Figs. 1 to 4 inclusive, the seat 26 is shown in the position when it is used to support the child in sitting posture, that is, the seat is in its forward position wherein the grooved rear end edge is in engagement with the round strut 24.

The springs 29 retain the rear end of the seat in engagement with the strut 24, and the small plate 32 which extends under the strut 24 retains the rear end of the seat against vertical displacement.

When the device is to be used as a walker in training the child to walk, the seat 26 is adapted to be slidably shifted rearwardly into the position shown in Fig. 4, and when in such position, the child may readily assume a standing position within the enclosure 15 so that it can walk while supported by its arms on the tray 12.

The seat 26 may be shifted rearwardly simply by first moving it slightly forward to release the engagement of the retainer 32 from underneath the strut 24 and then slightly lifting the seat and moving it rearwardly over the strut 24 for support thereon, and in this movement the front strut 23 will be engaged within the U-shaped clip 33 whereby the front end of the seat will be retained against vertical displacement while the depending lateral lip 34^a of the Z-bar 34 will prevent accidental forward and upward displacement of the seat.

In the modification illustrated in Figs. 5 and 6, the arrangement of the springs 29 is such that same tend to move the seat 26 forwardly.

As shown in Figs. 5 and 6, the seat 26 is shown in its foremost position wherein the Z-shaped retainer 35 engages beneath the front strut 23 and retains the seat against further forward movement and also against vertical displacement. A similar retainer 36, secured to the rear of the seat, also functions to retain the seat against forward and vertical movement when the device is used as a walker.

To convert the modified device from use as a chair to that of a walker, the seat 26 is slightly lifted at its rear end and moved rearwardly to the position shown in Fig. 5, by the dot-and-dash lines, wherein the Z-shaped retainer 36 engages with and under the rear strut 24 to resist forward and vertical displacement of the seat. In such rearward movement of the seat 26, the Z-shaped retainer 37 will be positioned to engage under the front strut 23 to thereby retain the front end of the seat against vertical displacement.

Various changes in the details of the preferred construction, shown in the attached drawing, may be readily made by those skilled in the art to which this invention appertains; hence, I do not wish to be understood as limiting myself to the particular details of construction shown as illustrative as one embodiment of my invention which is defined in the appended claims.

I claim:

1. In a child's combined chair and walker device, the combination with a plurality of caster-supported uprights and a horizontal tray carried by said uprights, of a slidably mounted seat adjustably supported below said tray, and means for retaining said seat in forwardly or rearwardly adjusted positions, including resilient means urging said seat rearwardly of the device, and an abutment for retaining the seat in its forward position against the pressure of said resilient means.

2. In a child's combined chair and walker device, the combination with a plurality of caster-supported uprights and a horizontal tray carried by said uprights, of a slidably mounted seat adjustably supported below said tray, and means for retaining said seat in forwardly or rearwardly adjusted positions, including resilient means urging said seat rearwardly of the device, an abutment for retaining said seat in its forward position, a retainer on the rear end of said seat preventing vertical displacement of the rear end of said seat, and a retainer on the front end of said seat for retaining said seat against vertical displacement when said seat is positioned in its rearmost position to permit use of the device as a walker.

3. In a child's chair and walker device, the combination with a plurality of caster-supported uprights and a horizontal tray carried by said uprights, of an enclosure for the child's trunk disposed below said tray, and having walls disposed in close proximity to the child's trunk, and a slidable seat adjustably supported at the lower end of said enclosure, wherein said enclosure consists of a structure of substantially rectangular cross-section having spaced openings in the front wall thereof for passage therethrough of the child's legs whereby a central portion of said front wall is disposed between the child's legs, and wherein said seat is provided with a forwardly disposed central extension of a width less than the width of the seat, said seat having spaced front edge portions disposed a space distance rearwardly of the inner face of the front wall, and said extension being disposed between the child's legs in vertical alignment with said front wall central portion.

4. A child's convertible chair and walker device comprising a plurality of caster-supported uprights, a tray carried by said uprights and provided with an opening for the child's body, a walled enclosure structure disposed below said tray for enclosing the major portion of the child's trunk, a laterally adjustable seat slidably supported on the lower end of said enclosure structure, said enclosure structure having opening means permitting passage of the child's legs therethrough, a front horizontal strut connecting a pair of the front uprights, a rear horizontal strut connecting a pair of the rear uprights, said seat having a narrow central front extension disposed to extend between the child's legs and positioned for support upon said front strut, the rear end of said seat being adapted to abut with said rear strut when the device is employed as a chair, resilient means urging said seat rearwardly, an abutment on the rear end of said seat adapted to engage said rear strut, for retaining said seat against forward movement when said seat is moved rearwardly to permit use of the device as a walker.

5. A device as embodied in claim 4 and wherein said abutment includes an extension preventing

vertical displacement of the rear end of said seat, and including means on said seat extension preventing vertical displacement of the front end of the seat when said seat is moved rearwardly to permit use of the device as a walker.

6. In a child's combined chair and walker device, the combination with a plurality of caster-supported uprights and a horizontal tray carried by said uprights, of a slidably mounted seat adjustably supported below said tray, and means for retaining said seat in forwardly or rearwardly adjusted positions, including resilient means urging said seat rearwardly of the device, a front

5 abutment on the front side of the device, retaining means on the front end portion of said seat adapted to engage said front abutment to retain the front end of said seat against forward and vertical displacement when the device is used as a chair, a rear abutment on the rear side of the device, and retaining means on the rear end of said seat adapted to engage said rear abutment to retain the rear end of said seat against forward and vertical displacement when the device is used as a walker.

JOHN MICHELIC.
